UNITED STATES PATENT OFFICE.

WELLINGTON J. SMITH, OF CLEVELAND, OHIO.

THERMOSTAT.

Application filed August 24, 1926. Serial No. 131,241.

This invention relates to a thermostat controller, and particularly to a construction embodying a metallic bar of thermostatic character disposed to cooperate with a make-and-break circuit mechanism for the purpose of maintaining a uniform predetermined temperature in a compartment.

The invention especially relates to the circuit contact members comprising a fixed contact and a lever or movable contact having one end disposed in the path of a thermostatic bar so as to be thereby actuated together with means by which the contact members may be adjusted relative to the bar.

15 The invention has for an object to provide a novel and improved construction in which a contact closing unit is mounted for adjustment relative to the free end of a thermostatic metal bar so as to thereby determine 20 the temperature to be maintained in the compartment in which the heating means is controlled by the thermostat.

A further object of the invention is to provide an improved construction of the circuit contact members in which the movable member comprises a pivoted lever normally tensioned towards a fixed contact and adapted 25 to be moved against said tension in the expansive action of a thermostatic metal bar.

30 Another object of the invention is to provide the contact members as a unit construction mounted upon an adjusting device by which they may be bodily shifted so that the circuit to an electric heater will be opened 35 at the proper temperature dependent upon the adjustment previously made and controlled by the expansive capacity of the thermostatic bar under the temperature of the compartment.

40 Other and further objects and advantages of the invention will be hereinafter set forth and the novel features thereof defined by the appended claims.

In the accompanying drawing:—

45 Figure 1 is a side elevation of the device applied, with parts in section;

Figure 2 is a plan thereof;

Figure 3 is an end view; and

50 Figure 4 is a detail perspective of the contact members.

Like reference numerals designate corresponding parts throughout the several figures of the drawing.

The invention is designed for various ap-

plications and for the control of different 55 heating devices, and in the form here shown comprises an insulating base 10 adapted to be mounted within a compartment 11 to be heated which may be a brooder, insulator, or other enclosure adapted to be heated by 60 an electric heater, as indicated at 12, having a current source at 13. The base 10 has mounted at one end thereof a bar or arm 14 of suitable thermostatic character such as the ordinary laminated metals, this bar being 65 offset from the base and secured thereto at 15. The free end 16 of the bar is adapted for expansion and contraction toward and from the base as indicated by dotted lines in Figure 1 and overlaps a circuit contact lever 70 17. This lever may be of various constructions, a desirable form being herein shown as pivoted at 18 in the depending ears 19 of a frame 20. This frame is formed with a depending arm 21 carrying a fixed circuit 75 contact 22 from which a conductor 23 extends to the heater 12 or other device.

Cooperating with the contact 22 is the movable contact 24 carried by the end of the lever 17 and normally tensioned toward the fixed 80 contact by a spring 25. This spring maintains the contacts in closed position establishing a heating circuit and such circuit is broken by the engagement of the free end 16 of the thermostatic bar with the end 26 of the 85 lever 17, as indicated in Figure 1. For the purpose of spacing the ends 16 and 26 to control the temperature at which the circuit will be opened, an adjusting device of suitable character is mounted upon the base 10. This 90 may comprise a screw 27 threaded through the base and connected by a swivel at 28 with the frame 20 carrying the contact members so that they are bodily adjusted. The screw is provided with a hand hold 29 extended 95 through the casing of the compartment to be heated and the movement of the unit carrying the contact members is guided by one or more pins 30 extending through an aperture in the lug 31 from the frame 20. The contact mem- 100 ber 24 upon the lever 17 is connected to the conductor 32 in any desired manner, for instance by a link 33 which forms a convenient means of application.

The operation of the invention will be apparent from the foregoing description from which it will be seen that the contact members are normally closed until the tempera- 105

ture of the compartment is raised to a degree sufficient to actuate the thermostatic bar which by its contact with the movable member opens or breaks the circuit and thus provides means for maintaining a predetermined uniform temperature in the compartment. The mounting of the contact members in a separate unit provides for the convenient application and replacement thereof and also maintains these members on a common center so as to secure a proper cooperation irrespective of the position of the thermostatic arm in its expanding and contracting movements. The bodily adjustment of this unit relative to the arm provides for the determination of the desired temperature to be maintained without affecting the relative positions of the contact members but merely changing their spaced relation to the thermostatic member. While the specific construction of the invention has been shown and described, the invention is not confined thereto as changes and alterations may be made without departing from the spirit of the invention and the

controlling members applied to a circuit for 25 the control of any desired device.

I claim:

1. In thermostatic controlled apparatus, the combination with a support, of a frame movably carried thereby, an arm outstanding from the frame and having a return portion substantially parallel to the frame, a lever pivoted to the frame and having a portion extending between the frame and return portion of the arm, a contact carried by the 30 return portion of the arm, a contact carried by the lever in position to engage the first mentioned contact, and thermally controlled means for swinging the lever for breaking such contact.

2. A unit for a thermostatic controller comprising an adjustable frame having a depending portion carrying a fixed contact, ears extending from said frame, and a lever pivoted intermediate its ends to said ears and carrying a contact member.

In testimony whereof I affix my signature.
WELLINGTON J. SMITH.
